UNITED STATES PATENT OFFICE

OTTO JOHN KUENHOLD, OF CLEVELAND, OHIO

DRYING APPARATUS

Application filed August 10, 1923. Serial No. 656,702.

This invention relates to drying apparatus, such as is used, for example, in household laundries and the like. More particularly, the invention relates to drying apparatus of 5 cabinet form including an air heating chamber, a clothes drying chamber, suitable devices on which the clothes may be supported, and the necessary means for producing proper flow or circulation of air through the drying 10 chamber.

The present application is a companion to another application for drying apparatus, filed of even date herewith, Serial No. 656,701. The invention of the present application relates more particularly to a special form and arrangement of cabinet and drying racks on which the clothes to be dried are supported, said racks being arranged to be offset from each other in a direction parallel to the planes 20 of the racks when they are in closed position in the drying chamber and lying in substantially parallel relation when opened out perpendicular to the drying chamber, for the purpose of affording maximum access to all 25 racks for loading and unloading the same, such effects being obtained by special arrangements of the racks and pivots therefor as more particularly described hereinafter.

In the drawings, Fig. 1 is in part a front 30 elevation, showing one of the cabinet doors open, and in part a broken out sectional elevation on the line 1—1, Fig. 2; Fig. 2 is in part an end view from the right in Fig. 1 and in part a sectional elevation on the line 2—2, 35 Fig. 1; Fig. 3 is a sectional plan view on approximately the line 3—3, Fig. 1; Fig. 4 is a similar view on the line 4—4, Fig. 1; Fig. 5 is a detail sectional elevation on the line 5—5, Fig. 1; and Figs. 6 and 7 are detail plan views 40 illustrating modified forms of drying racks.

Referring to the drawings the apparatus comprises a suitable cabinet including an upper member 1 in which is a drying chamber 2 closed by doors 3, and below which is a 45 lower member 4 having a heating chamber 5, and which member serves as a support for the upper member, being separated therefrom by a horizontal wall 6 provided with screened openings 7 and 8. Except for differences 50 hereafter described the construction and ar-

rangement of this cabinet is similar to that of my companion application before referred to, to which reference may be had for a more complete description where necessary. Said companion application illustrates a gas 55 heater for the air current. In the present application, adapted especially where gas is unavailable for fuel, the heater is of electric form, comprising a grate or grid formed of longitudinally extending parallel electrical 60 heating elements 9 suitably connected in a circuit controlled by the switch 10. Air enters the lower casing member through an inlet 11 controlled by a damper 12, said air flowing to and through the chamber 5, being 65 diverted upwardly by the deflectors or baffles 13 to cause it to pass through the spaces 14 between neighboring heating elements 9 and through the screened opening 7 to chamber 2 in which it rises, following the general course 70 of the arrows A, and flows downwardly through the screened opening 8 to a chamber 15 from which it issues through the outlet 16. 17 represents a shallow pan or receptacle 75 suitably supported above the heating elements 9 and below the screened inlet 7 for containing a germicide or bleaching, disinfecting or deodorizing material of such form as to be taken up or absorbed by the air stream and carried over and around the material to be so dried. The flow of air along the path described is partly by convection, due to the air current rising from the heater, or may be more or less induced or accelerated by a suitable fan 18 controlled by a switch 19, the 85 velocity of flow being also capable of control by damper 12, so as will be readily understood.

The materials to be dried are supported upon suitable racks in the drying chamber 2. These racks, of which any number may be 90 used, are located in parallel vertical planes and are arranged so as to be capable of swinging out to an open position perpendicular to the general planes of the racks when closed. The rear rack is fixed or stationary, consisting 95 of horizontal members 20 suitably supported in the casing. The three front racks are of special form and arrangement. Each of these racks comprises two vertical side members 21, formed for example, of metal pipes 100

connected by wooden horizontal cross bars 22, the latter being split at their ends, as at 23, and provided with openings to receive the pipes 21, the parts being attached by clamping screws or bolts 24 which firmly clamp the ends of the wooden bars to the pipes. One of the end pipes or bars of each rack is provided at top and bottom with fittings or arms 25 carrying vertically extending pivot members 26 entering aligned openings in the roof and floor respectively of the drying chamber. The upper of such pivots may be slightly nearer the door opening than the lower so that each rack has a natural tendency to spring 15 toward open position or outwardly from the drying chamber. It will be understood that as the racks are pushed back to their closed positions, shown in full lines Fig. 4, pins 29 thereon ride up along the inclined edge of a 20 suitable bracket 30 with slight rising motion of the entire frame in the drying chamber until the pin reaches its seat in the recess, being releasably held there by gravity.

The pivots for the several racks may be arranged in various ways. In Fig. 4 the pivots 26 are offset from the median planes of the several racks different distances, but all in the same direction. In other words, the arm for the front rack is short and extends forwardly, while the arm for the third rack is longer but also extends forwardly. Also, as shown in Fig. 4, the several racks are offset or in staggered relation in the direction of the planes of said racks when closed. As a 35 result they are offset or lie in spaced parallel arrangement when closed, and are also offset but lie in closely neighboring parallel relation when open, as shown in dotted lines, Fig. 4. In Fig. 6 the same arrangement of arms 40 offset from the planes of the racks is used, but the several racks lie in registering relation with each other when closed within the drying chamber. In Fig. 7 the several racks are offset from each other in the direction of the 45 planes of said racks but the pivots lie each within the median plane of its particular rack, so that the pivots are offset or in stepped relation in the planes of the racks, but not perpendicularly thereto.

50 Other arrangements are obviously suitable for the purpose.

What I claim is:

1. Apparatus of the class described, comprising a cabinet provided with a chamber, a 55 series of material supporting racks pivotally mounted upon different vertical axes therein, the axes of the several racks being offset different distances from the median planes of said racks.

60 2. Apparatus of the class described, comprising a cabinet provided with a chamber, a series of material supporting racks pivotally mounted upon different vertical axes therein, the axis of the several racks being offset 65 different distances perpendicularly from the

median planes of said racks, whereby said racks lie parallel to each other when closed within and opened out from the chamber, the offset distance of the axis of each rack being less than the distance between said 70 rack and the next adjacent rack.

3. Apparatus of the class described, comprising a cabinet having an open front and a door for closing the same, in combination with a plurality of material supporting racks, each rack having substantially vertically aligned pivot members near one end thereof, and cooperating pivot receiving means on the cabinet at one side of the door opening, the pivotal axes for the several racks being 80 located both in progressively varying horizontal relation to the several racks and also in and to the cabinet and all lying in the same substantially vertical plane in such manner that said racks are spaced apart in parallel relation when within the cabinet and lie in closely neighboring parallel relation when swung out at right angles from the cabinet.

4. Apparatus of the class described, comprising a cabinet provided with an open front and a door for closing the same, in combination with a plurality of material supporting racks within said cabinet, and pivotal mountings for said racks including means so positioned as to cause the racks when swung to move from spaced parallel relation in the cabinet to close neighboring parallel relation when projecting at right angles therefrom.

5. Apparatus of the class described, comprising a cabinet having an open front and a door for closing the same, in combination with a plurality of material supporting racks, each rack having substantially vertically aligned pivot members near one end thereof, cooperating pivot receiving means on the cabinet at one side of the door opening, said racks having stop pins located at different levels at their free ends, and a stationary bar having a series of recesses one for each stop pin and adapted to receive the same as the 110 racks are moved to their inner positions.

6. Apparatus of the class described, comprising a cabinet provided with a door closed opening in its front wall, a series of material supporting racks pivotally mounted upon substantially vertical axes at one side of said opening, each rack having substantially aligned upper and lower pivots, pivot supporting means on the cabinet in which said pivots are slidable vertically, and common means at the other side of said opening for supporting engagement with the free ends of said racks for elevating said racks as they move to positions within the cabinet.

7. Apparatus of the class described, comprising a cabinet provided with a door closed opening in its front wall, a series of material supporting racks pivotally mounted upon substantially vertical axes at one side of said opening, each rack having substantially 125

aligned upper and lower pivots, pivot supporting means on the cabinet in which said pivots are slidable vertically, and latching and supporting means for said racks, comprising a bar mounted in the cabinet and inclined downwardly toward its front, and a projection on each rack adapted to ride upwardly along said bar and elevate the rack as it moves into the cabinet.

10 8. Apparatus of the class described, comprising a cabinet provided with a door closed opening in its front wall, a series of material supporting racks pivotally mounted upon substantially vertical axes at one side of said opening, each rack having substantially aligned upper and lower pivots, pivot supporting means on the cabinet in which said pivots are slidable vertically, and latching and supporting means for said racks, comprising a bar mounted in the cabinet and inclined downwardly toward its front, and a projection on each rack adapted to ride upwardly along said bar and elevate the rack as it moves into the cabinet, said bar having 25 a series of recesses, one for receiving each of said projections, for holding the racks in the cabinet.

9. Apparatus of the class described, comprising a cabinet provided with a chamber, a series of material supporting racks pivotally mounted upon different vertical axes therein, the axes of the several racks being offset perpendicularly from the median planes of said racks, whereby said racks lie parallel to each other when closed within and opened out from the chamber, the offset distance of the axis of each rack being less than the distance between said rack and the next adjacent rack.

40 In testimony whereof I hereby affix my signature.

OTTO JOHN KUENHOLD.
